UNITED STATES PATENT OFFICE.

EDMUND H. LUNKEN, OF CINCINNATI, OHIO.

SCREEN FOR POCKET-WINDOWS.

1,245,249.

Specification of Letters Patent.

Patented Nov. 6, 1917.

Application filed May 23, 1916. Serial No. 99,304.

To all whom it may concern:

Be it known that I, EDMUND H. LUNKEN, a citizen of the United States, and a resident of Cincinnati, in the county of Hamilton and State of Ohio, have invented certain new and useful Improvements in Screens for Pocket-Windows, of which the following is a full, clear, and exact description, reference being had to the accompanying drawing, forming part of this specification.

My invention relates to screens for use in pocket windows of the type wherein the sashes are slidable in the frame of the window and the pocket is located above the window opening and is of sufficient size to receive both sashes. The building of a pocket in the walls of a building is a simple operation unless the pocket is too deep for standard construction. Thus while it is very convenient to have a pocket above a window opening within which the window screens may be pushed, still to allow for two sliding screens in a wall pocket as well as two sashes of standard thickness, and the parting strips of the side sash rails, takes up more space than standard construction will allow between the inner and outer walls of a building.

The screens for a pocket window must, however, be sufficient to inclose the entire window opening, instead of but half of it as is the present practice, and since there is no room in a wall pocket for two sliding sashes and two screen members, some other form of screen and some other means of mounting it in the wall pocket during the winter months should be provided to get the full usefulness out of a wall pocket.

It is accordingly my object to provide a screen for pocket windows which is quickly and easily mountable in the window opening, and which has means of being supported in the pocket, during the winter months, in the pocket space usually employed for the lower sliding sash of the window, whereby said screen may be stored in the pocket of the window frame where it is to be used during the warmer months of the year.

The structure of the screen so as to enable it to be easily and quickly put in place and held in position for use is one of the particular objects of my invention and also it is my object to provide for adjustment of the screen in the window opening so as to

allow for unexpected variations in size of the window openings.

These objects and other advantages to be noted I accomplish by that certain construction and arrangement of parts to be hereinafter more specifically pointed out and claimed.

In the drawing,

Figure 1 is a fragmentary perspective view of the screen.

Fig. 2 is a vertical sectional view through a window showing the arrangement for storing the screen.

Fig. 3 is a detail vertical section through the adjusting device for the top of the screen.

Fig. 4 is a view on a larger scale of the upper portion of Fig. 2.

Fig. 5 is a detail perspective of one of the retaining plates for holding the screen in the pocket of a window.

The window frame has the usual side rails 1, 1, for the sliding sashes. These rails extend up into the pocket 2 and have the necessary parting strip 3 between the two sashes 4 and 5. The pocket is of a size to receive the sashes, but it is not large enough to receive also a pair of sliding screens for the reason above expressed, that to make it so would require a modified construction that would change the whole structure of the house, from standard to special construction.

Mounted on the side rails in the window opening are two angle iron strips having one portion 6 lying along the rails and the other portion or flange 7 extending laterally into the window opening. At the base, this flange 7 is bent out along the sill 8 of the window frame and then upwardly at 9 to form a channel for engaging the lower corner of the screen. The flanges 7 have also suitable apertures 7a in their upper ends for mounting the screens.

The screens are in two sections, the upper 10, and the lower 11. There are hinges 12, 12, to join the two screens together, and these are preferably mounted so as to bring the abutting edges of the two screens so close together that they will not leave a gap between the screens. On the top of the screen 10 for the upper part of the window is mounted a plate 13 which is slotted at 14 to receive screws 15 that screw into the upper rail of the said screen. This plate has mounted on it the sliding pins 16 which

are adapted to slide into engagement with the holes or apertures 7^a in the upper end of the angle iron member 7 above mentioned. The loosening of the screws 15 will 5 result in allowing this plate 13 to be adjusted on the top of the upper screen a distance equal to the length of the slots 14 in said plate.

The hinges on the two screen members are 10 provided with a special pintle 17 which has a return bend 18 on its inner end and the shank of which is quite long so as to permit of the moving outward of the outer end without separating the hinge members. 15 There is also formed a suitable stop 17^a on the pintle to prevent its removal.

As so constructed, the screens are mounted in the window as follows. The upper screen member is secured in the apertures in the 20 angle iron strip by pushing the two pins 16 on the plate 13 into said apertures. Since the screen is hinged at the middle it can be swung outwardly from the window and the lower edge of the lower screen member 25 dropped in behind the tongues or bends 9, thereby securely seating the lower screen member in the channel formed by said tongues. The hinged portion of the screens are then drawn up against the angle iron 30 flange 7, by means of the handles formed on the hinge pintles as above noted, and the said pintles are then moved outwardly and the ends brought over the inside of the said flange 7.

35 If the lower end of the lower screen does not properly seat at the base as above noted, the plate 13 is adjusted, by loosening the screws and allowing the screen to be raised or lowered with regard to said plate until it 40 is properly seated at the base. The screen is then not only securely held in the window so as to protect the entire opening, but it is also locked on the inside by means of the hinge pintles, thereby preventing access to 45 the inside of the window from the outside.

The screen may be opened to gain access through the window by sliding the pintles from locking position, lifting the lower screen out of the channel in which it is 50 seated. By pressing the screens outwardly and raising with the hinge handles the lower corners are lifted out of the angles 9.

For removing the screen, one of the pins at the top is drawn out of engagement, the 55 hinge pintles released and the screen raised out of the lower channel. The screen may then be tipped out at the top and allowed to flex outwardly at the middle with the lower edge of the screen held against the sill angle 60 9. The operator may then grasp the partly folded screens at the middle and bring them sidewise into the inside of the window.

On the outside of the lower screen are two 65 headed pins 19. Set flush in the front wall of the pocket, near the window opening, are

two socket plates 20, having slots 21 larger than the heads of the pins, and preferably an elongated narrow slot at the base. In the top of the pocket is formed a channel to receive the top of the folded screens, by means 70 preferably of a strip 22 screwed to the pocket top.

For mounting the screens in the pocket, therefore, they are folded together and pushed up into the pocket till their upper 75 ends seat in the channel above mentioned. The pin heads are then moved into the holes in the socket plates, and the screens allowed to settle down, with the pins securely held in the said holes, or lower end of 80 the narrow slots.

The screen as so mounted can remain over the winter, unless it is desired to raise the lower window sash into the pocket. This is not usually desired in the winter, and accordingly the screen is not in the way of the usual winter use of the window. The position of the screen at the front of the pocket acts as a stop for the lower sash, as its top rail will contact with the lower edge of the 85 bundle of screens, thereby preventing the wedging of the sash and screens together by 90 a careless raising of the lower sash.

It would, of course, be much simpler to provide a sliding screen in a pocket window and simply slide the screens up into the pocket when not in use, but as explained at length above, this is not practical. The screen provided by me as above described, is therefore 95 not of the sliding type, as this type is difficult of removal, particularly if there are two sliding screens as are necessary in a pocket window where the protection of the entire window opening is called for at times.

Having thus described my invention, what 100 I claim as new and desire to secure by Letters Patent, is:—

1. In combination with a window having an opening, a sash, and a sash receiving pocket above said opening, a screen for said opening comprising screen members hinged together, means for supporting said screen in the window opening, and means on the screen and in the sash pocket for holding the screens within said pocket and free of 110 the window sash for purposes of winter storage.

2. A screen for pocket windows of the character described, comprising screen members hinged together and adapted to fill the 120 window opening when unfolded, and to fit the pocket of said window when folded, and means on the screens and in the pocket portion of the window for supporting said screens within the pocket, said means comprising a channel or socket therefor at the upper end of the pocket, pins on the screens and sockets in the lower portion of the pocket to receive said pins.

3. In a pocket window, a window frame 125

having a window opening and a pocket above it, a plurality of sliding sashes, a plurality of screens connected together and of the size of said sashes, means to retain the 5 screens in the window opening, and means to retain them at the top and adjacent the orifice of the pocket in the place occupied by one of the window sashes.

4. In a window screen to completely screen 10 a window opening, the combination with an abutment strip in the window opening, of a screen member, means thereon for suspending said member at the upper end of the window, means for adjusting the screen on 15 said supporting means, and means for retaining the screen against the strip.

5. In a window screen to completely screen 20 a window opening, a plurality of screen members hinged together, means for pivotally mounting the upper screen member to the window, means on the window engaging the lower end of the lower screen member, and means for locking the two screens against the window frame.

25 6. In a window screen, a plurality of

screen members, means for pivoting the top member in a window opening, hinges for hinging the screens together, pintles for the hinges, means for holding the lower screen to the base of the window, said pintles being 30 movable laterally in the hinges, for the purpose described.

7. In a window screen, a plurality of 35 screen members pivoted together, means for detachably pivoting the top member in a window frame, a channel forming member for seating the bottom member of the screen, and means for locking the screens to the window adjacent their pivot point.

8. In a window screen, a plurality of 40 screen members, means for detachably pivoting the top member in a window frame, a channel forming member for seating the bottom member of the screen, and means for locking the screens to the window adjacent 45 their pivot point, said means comprising sliding pins, and a flange in the window over which said pins are to be engaged.

EDMUND H. LUNKEN.
